UNITED STATES PATENT OFFICE.

FREDERICK W. PEISCH, OF CHICAGO, ILLINOIS.

PHONOGRAPH-NEEDLE.

1,370,763.

Specification of Letters Patent.

Patented Mar. 8, 1921.

Application filed February 10, 1919. Serial No. 276,242.

To all whom it may concern:

Be it known that I, FREDERICK W. PEISCH, a citizen of the United States, and a resident of the city of Chicago, county of Cook, and State of Illinois, have invented certain new and useful Improvements in Phonograph-Needles, of which the following is a specification.

My invention relates to improvements in phonograph needles and has for its object the provision of an improved construction of this character by means of which a needle is provided, capable of producing varying tones and also capable of prolonged use and ready renewal.

Other objects will appear hereinafter.

The invention consists in the combinations and arrangements of parts hereinafter described and claimed.

10 The invention will be best understood by reference to the accompanying drawings forming a part of this specification, and in which,

Figure 1, is a perspective view of a phonograph needle embodying the invention,

Fig. 2, an end view of the same, and

Fig. 3, a longitudinal section of the same.

The preferred form of construction, as illustrated in the drawings, comprises a holder in the form of a rod split diametrically into two separable parts 4 and 5, said parts being provided with external annular registering grooves 6 to contain binding wires for binding the two parts together.

30 35 The part 5 is provided in its inner face with a longitudinal V-shaped groove or bore 7 extending the full length thereof and adapted to receive a section of fine steel wire 8, as indicated. The arrangement is such that

40 the steel wire 8 will be frictionally clamped in the groove 7 so as to be held in place with sufficient force to permit of the use of the same as the stylus or sound transmitting member of an ordinary phonograph, but

45 loose enough to permit of the ready longitudinal adjustment of said wire in said holder. Best results will ordinarily be attained by adjusting the wire 8 until the same protrudes from the operative end of the

50 holder 4—5 a comparatively short distance or about from one thirty-second to three sixty-fourths of an inch. By increasing the length of operative wire protruding from the holder, the tone emitted by the instrument

55 may be softened, and vice versa. As the wire 8 wears, the same may be adjusted

through the holder until the greater portion thereof has been thus consumed, whereupon the remaining small end may be removed and a new length of wire substituted therefor. By virtue of these longitudinal adjustments, not only may the tone be varied as desired, but the life of the needle greatly prolonged and readily renewed when consumed.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. A phonograph needle comprising a split holder; means for circumferentially binding the portions of said holder together; and a wire contact member frictionally clamped between the portions of said holder and freely adjustable longitudinally therein, substantially as described.

2. A phonograph needle comprising a holder in the form of a split rod having a bore extending therethrough; wires binding the portions of said rod together; and a contact member frictionally clamped between the portions of said holder and freely adjustable longitudinally therein, substantially as described.

3. A phonograph needle comprising a holder in the form of a split rod, the meeting face of one portion of said rod being provided with a longitudinal V-shaped groove or bore extending the full length of said rod, there being external annular grooves adjacent the ends of said rod; binding wires positioned in said grooves and binding the parts of said rod together; and a wire contact member resting in said groove and frictionally clamped therein, substantially as described.

In testimony whereof I have signed my name to this specification in the presence of two subscribing witnesses.

FREDERICK W. PEISCH.
